UNITED STATES PATENT OFFICE.

HERBERT H. HART, OF ORCUTT, CALIFORNIA.

FAN-HOUSING COOLING EXTENSION.

1,275,682.

Specification of Letters Patent. Patented Aug. 13, 1918.

Application filed August 14, 1917. Serial No. 186,234.

To all whom it may concern:

Be it known that I, HERBERT H. HART, a citizen of the United States, residing at Orcutt, in the county of Santa Barbara and State of California, have invented new and useful Improvements in Fan-Housing Cooling Extensions, of which the following is a specification.

My object is to improve the lay-out and construction of a fan housing to be bolted on to the rear of the radiator of any type of automobile, motor truck, or the like, for the purpose of better cooling the radiator and engine, by producing a better suction of air, with the aid of the fan, through the tubes of the radiator, and concentrating this cool air directly on the engine.

Ordinarily, without my invention, the suction of air is only noticeable in a small spot directly in front of the fan and the cool air is distributed mostly around the hood of the engine where it does very little good.

Specifically, my object is to make a fan-housing cooling extension which may be readily applied or removed, which will form a close joint all around the radiator, which may be pressed tightly into place, which has non-metallic packing and cushions to form a tight joint and prevent rattling, and which will draw air through all parts of the radiating field and concentrate the air upon the hottest part of the engine.

The drawing illustrates the invention.

Figure 1 is a vertical cross-section showing my fan housing cooling extension in position for use and attached to the rear side of the radiator and extending backwardly around the fan, the view being taken on the line 1-1 of Fig. 2.

Fig. 2 is a vertical longitudinal section on the line 2-2 of Fig. 1.

Fig. 3 is a perspective of the fan housing cooling extension removed from the radiator and fan.

Fig. 4 is an enlarged fragmentary sectional detail on the line 4-4 of Fig. 1.

The radiator 1 has a dome 2 and this dome extends backwardly beyond the radiator tubes, thus producing a flat lower face 3 extending backwardly across the top of the radiator and below the dome. The side walls 4 of the radiator 1 extend backwardly beyond the tubes and form flanges 5 and the rear edges 6 of these flanges are off-set inwardly, as shown in detail in Fig. 4. Transverse flanges 7 extend inwardly from

the sides 4 immediately behind the tubes and at the forward edges of the flanges 5, thereby forming right-angled corners. The top of the engine jacket 8 is connected to the dome 2 by a pipe 9. The lower water chamber 10 below the tubes of the radiator 1 is connected to the lower part of the engine jacket by a pipe 11. The rear side of the chamber 10 has a vertical transverse flat face 12.

The details of the fan housing cooling extension 13 are as follows:

The body 14 is preferably stamped from sheet metal and has a circular central opening 15, the margin 16 around the opening 15 being substantially flat so that it will stand in a transverse vertical plane, as shown in Fig. 2. The intermediate portion 17 immediately surrounding the flat portion 16 is dished or curved and extends outwardly and forwardly from the flat portion 16, and the rim 18 is constructed to fit the radiator to which the housing is to be applied.

The overflow pipe 19 extends from the radiator cap 20 through the flat face 3 directly behind the pipe 9 and then extends laterally behind the tubes of the radiator 1 and downwardly inside of one of the flanges 5.

A flange 21 extends backwardly from the upper edge of the portion 17 and has a notch 22 at its center for the overflow pipe 19. A heavy felt packing and cushion 23 is secured to this flange 21 by rivets 24, and the flange and packing fits tightly against the flat lower face 3 of the dome. Attaching plates 25 and 26 extend vertically along the side edges of the portion 17 from the ends of the flange 21, said attaching plates being flat and in a transverse plane. Felt cushion and packing strips 27 are secured against the rear faces of these plates 25 and 26 by rivets and said packing strips fit against the transverse flanges 7. From the lower ends of the plates 25 and 26, the corners 28 and 29 and the lower edge 20 of the portion 17 are turned inwardly and upwardly to produce the flat flange 31, and a packing and cushion strip 32 is secured against this flange and fits against the face 12, there being a depression 33 to pass the pipe 11. When the extension is in place there is a practically airtight joint all the way around the rim 18.

Hinge members 34 are secured in horizontal alignment to extend from the plates 25 and 26 and each hinge comprises an at-

taching plate 35 secured to the portion 17, the hinge pin 36 being some distance inside of the outer edge of the plate 26. The second hinge member 37 is secured to the hinge pin 36 and has a portion 38 extending outwardly to the flange 5 and a portion 39 bent at right angles and fitting against the inner face of the flange 5, and a portion 40 extending backwardly from the portion 39 10 and fitting against the inner face of the off-set portion 6 and extending backwardly beyond the edge thereof. Screws 41 are inserted through the flanges 5 and are screw-seated into the portions 39 of the hinges.

15 When the fan housing cooling extension is about to be applied, the members 37 of the hinges are turned inwardly, as shown in dotted lines in Fig. 4, until the fan housing has been seated. Then the members 20 37 are pressed tightly outwardly to press the housing firmly into its seat, the portions 39 of the hinges fitting against the inclined faces 42 between the flanges 5 and the off-set portions 6, so that when the screws 41 25 are applied to draw the portions 39 tightly against the flanges 5, the extension will be firmly seated and pressed tightly against the packings and cushions. The packings and cushions serve to form tight joints and 30 to prevent rattling. The extended ends 43 of the hinge members 37 serve as handles for swinging the hinges into and out of position. The hood 44 of the engine fits against the outer faces of the extensions 6 35 and as soon as the hood is raised the handle portions 43 are accessible, as clearly shown in Fig. 4.

The opening 15 is smaller than the diameter of the fan 45 and the fan sets concentric to the opening 15 and substantially half way between the rear face of the radiator 1 and the edge of the margin 16 around the opening.

I have found by extensive experimenting 45 and use that this construction produces good results. The air is drawn through all parts of the radiating field and is concentrated and directed to the hottest part of the engine, instead of being thrown outwardly to 50 the hood.

I claim:

1. A fan-housing cooling extension comprising the combination with a radiator and fan, of a seat extending around the rear face of the radiating field, a dished plate 55 having an opening in its center, a rim upon the dished plate, a non-metallic packing and cushion upon the rim and fitting the seat, and hinges secured to the rim and screwed to the radiator to hold the rim tight against 60 the cushion and the cushion tight against the seat.

2. A fan housing cooling extension comprising the combination with a radiator and fan, of flanges extending inwardly from the 55 rear edges of the sides of the radiator in transverse alignment with the rear flat face of the bottom of the radiator, second integral flanges extending backwardly from the sides of the radiator beyond the first flanges, 70 a body formed of sheet metal and having a circular central opening; the margin around the opening being substantially flat in a transverse plane, the intermediate portion surrounding the flat portion being 75 dished, and the rim around the intermediate portion fitting the first flanges and the rear flat face, there being cushions secured to the rim between the flanges and flat face; hinges secured to the sides of the intermediate portion and engaging the second flanges, and means securing the hinges to the second flanges.

3. The combination with a radiator having flat transverse faces at its rear sides and 85 bottom, of a body formed of sheet metal and having a circular central opening; the margin around the opening being transversely flat, the intermediate portion around the margin being dished, and the rim around 90 the intermediate portion being flat to fit the flat faces of the radiator; and hinges secured to the sides of the body; there being integral flanges extending backwardly 95 from the radiator against which the hinges fit and there being means for securing the hinges to the flanges.

In testimony whereof I have signed my name to this specification.

HERBERT H. HART.
